Inventor:

John Henry Morgan,

By his attorney, W. H. Richard.

UNITED STATES PATENT OFFICE.

JOHN HENRY MORGAN, OF KENT, ENGLAND.

BRACKET FOR SHELVING AND THE LIKE.

1,347,116.

Specification of Letters Patent. Patented July 20, 1920.

Application filed December 26, 1919. Serial No. 347,548.

To all whom it may concern:

Be it known that I, JOHN HENRY MORGAN, a subject of the King of Great Britain, residing in Kent, England, have invented certain new and useful Improvements in Brackets for Shelving and the like, of which the following is a specification.

This invention relates to brackets for shelving and the like, and it has for its object certain improvements in such brackets designed primarily to secure a better distribution of the strain thrown by the load upon the bracket whereby the carrying limit of a bracket according to this invention shall be much greater than is the case with a bracket of the same size but of ordinary construction.

The invention further provides a bracket which when packed for transport or storage shall occupy a minimum amount of space.

A bracket according to this invention moreover affords much greater facilities for effecting its attachment to the wall or other support than is the case with brackets of ordinary construction.

In order that the invention may be the better understood reference may be had to the accompanying drawings forming part of this specification, in which:

30 Figure 1 is a front view of a bracket according to this invention.

Fig. 2 is a side view.

Fig. 3 is a plan to a large scale showing the inner end of the shelf carrying member.

35 Fig. 4 is a similar view showing the upper end of the part of the bracket which is secured to the wall.

Fig. 5 is a view showing the bracket with the parts in position for packing or storage.

40 Referring to the accompanying drawings *a* indicates the shelf supporting member formed of sheet metal having pressed or otherwise formed upon it a central rib *b* projecting downwardly from the flanges *b*¹, which flanges are provided with screw holes for the purpose of securing the shelf thereto. The inner end of the rib is slotted as shown at *b*⁴ and there are formed at this point on each side of rib *b* outwardly turned flanges *b*¹² perforated as shown at *b*³ for the passage of screws.

45 Pivots connected to the part *a* at point *c* is the second member indicated by *d* which member is of substantially the same form and construction as member *a* except that the rib *d*¹ thereon is arranged to pass within the slotted por-

tion *b*⁴ of rib *b*. The lateral flanges of part *b* are provided with holes for the passage of screws whereby said member is secured to the wall or other surface or body. 60 The perforations at the upper end of part *d* are so disposed that with the parts in position for use as shown in Figs. 1 and 2 the said perforations register with those in the flanges *b*¹² in part *a* the screws passing 65 therethrough serving not only as a means of attachment of the bracket to the wall but also form important elements in the strength of the bracket as they resist the crushing strain of the load. At the same 70 time when applying the bracket to the wall, the parts being in the position shown in Fig. 5, the holes for the screws can be marked off or formed with much greater ease than with the ordinary solid bracket 75 where the shelf arm is in close juxtaposition to said screw holes, and in addition to preventing the ready manipulation of the gimlet, bradawl or other tool, it is apt to cause injury to the hand of the person operating 80 said gimlet or the like. When the screw holes have been marked off or made in the wall the parts may be brought into the position for use, the screws for fastening to the wall at the upper end of the members *a* 85 and *d* passing through flanges *b*¹² and through the part *d* adjacent thereto.

It will be noted that the part of the bracket secured to the wall is less in length than that carrying the shelf. This shortening of the part *d* is possible for the reason that with the construction described the function of part *d* is simply to carry the part *a* and said part *d* is not called upon, as in the case of an ordinary wall bracket, 95 to bear the leverage strain consequent upon the construction of said bracket, and the tendency of which is to tear the wall plate from the wall. In place of a leverage strain the bracket is called on to sustain a shear- 100 ing strain which falls directly upon those parts best calculated to resist it viz: the pivot *c* and screws adjacent thereto.

Obviously instead of being formed of sheet metal the bracket may be formed of 105 cast or other suitable metal.

Having thus described my invention, I claim:

1. A bracket comprising a flanged supporting arm and a flanged attaching arm 110 pivotally connected thereto near the inner ends of the arms, the supporting arm being

- provided with extending flange portions for engaging adjacent flange faces of the attaching arm to sustain the strain upon the supporting arm, and means engaging said flange portions and engaging said adjacent flange faces for retaining the flange portions and flange faces in engagement, and for securing the arms to a plane surface in operative relation to each other.
2. A bracket comprising a flanged supporting arm and a flanged attaching arm pivotally connected thereto near the inner ends of the arms, the supporting arm being provided with extending flange portions for engaging adjacent flange faces of the attaching arm to sustain the strain upon the supporting arm, and means engaging said flange portions and engaging said adjacent flange faces for retaining the flange portions and flange faces in engagement, and for securing the arms to a plane surface in operative relation to each other; the arms when in normal operative position being at right angles to each other and the supporting arm being movable radially relative to the attaching arm.
3. A bracket for shelving comprising a shelf arm and a wall attachment arm, the arms when in normal operative position being at right angles to each other, the shelf arm being provided with flanges arranged for securing a shelf to the upper surfaces thereof and provided with a central downwardly extending rib having a slot therein at the inner end of the rib and laterally extending flange portions adjacent to said slot, said wall attachment arm being provided with flanges arranged for attaching the arm to a wall surface and being provided with an inwardly extending central rib pivotally connected near its upper end to the inner end of the rib of the shelf arm and engaging in said slot, said laterally extending flange portions engaging adjacent flange faces of the wall attachment arm, and means engaging said laterally extending flange portions and engaging said adjacent flange faces for retaining the flange portions and flange faces in engagement, and for securing the arms to a wall surface in operative relation to each other; the central rib of the shelf arm being rounded at the inner end thereof to permit radial movement of the shelf arm relative to the wall attachment arm.

ing in said slot, said laterally extending flange portions engaging adjacent flange faces of the wall attachment arm, and means 45 engaging said laterally extending flange portions and engaging said adjacent flange faces for retaining the flange portions and flange faces in engagement, and for securing the arms to a wall surface in operative 50 relation to each other.

4. A bracket for shelving comprising a shelf arm and a wall attachment arm, the arms when in normal operative position being at right angles to each other, the shelf 55 arm being provided with flanges arranged for securing a shelf to the upper surfaces thereof and provided with a central downwardly extending rib having a slot therein at the inner end of the rib and laterally extending flange portions adjacent to said slot, said wall attachment arm being provided with flanges arranged for attaching the arm to a wall surface and being provided with an inwardly extending central rib pivotally 60 connected near its upper end to the inner end of the rib of the shelf arm and engaging in said slot, said laterally extending flange portions engaging adjacent flange faces of the wall attachment arm, and means 70 engaging said laterally extending flange portions and engaging said adjacent flange faces for retaining the flange portions and flange faces in engagement, and for securing the arms to a wall surface in operative relation to each other; the central rib of the shelf arm being rounded at the inner end thereof to permit radial movement of the shelf arm relative to the wall attachment arm.

80 In witness whereof I have hereunto set my hand.

JOHN HENRY MORGAN.
